UNITED STATES PATENT OFFICE

JAMES CAMROD LEDBETTER, OF NEW YORK, N. Y., ASSIGNOR TO THE PROSPERITY COMPANY, INC., OF SYRACUSE, NEW YORK, A CORPORATION OF NEW YORK

CONVEYER GARMENT PRESS

Application filed June 4, 1927. Serial No. 196,416.

This invention relates to presses and in particular to a conveyer garment press which is capable of increased production and requires a minimum of floor space.

Though my invention relates in general to garment presses, I have illustrated herewith a hosiery press, and an object is to produce a pressing machine, capable of pressing, drying, and capable of printing, stamping or 10 trade-marking garments such as hosiery, the characteristic feature residing in a small size, upright vertical machine having the pressing and drying jaws located high off of the floor and above the operator's head in order that the work be executed away from the 15 operator.

One of the objects of my invention in locating the pressing jaws high above the operator is to afford more pleasant working environments and this is accomplished by reason 20 of the fact that the heat which radiates from the jaws of the press does not come in close contact with the operator because of the fact that the heated jaws are out of reach, and 25 the heat radiating therefrom has a tendency to rise and not to heat the lower strata of air adjacent the floor and around the operator.

Another important feature and object of this invention resides in the provision of conveying means whereby the garments carried 30 on hosiery forms are moved up into the jaws and moved down therefrom, the line of travel being substantially vertical thus bringing the hosiery forms to rest at a point directly in 35 front of the operator where it is convenient to remove the pressed, dried and printed garments from the forms and replace new work thereon.

An additional object is to produce a double 40 capacity hosiery conveyer or tray carrying two independent sets of hosiery forms whereby one batch or quantity of garments is being pressed and made ready for printing while the other batch or quantity of garments which 45 were previously pressed are undergoing a printing operation; and the arrangement is such that a number of stockings are finished, completely pressed and printed each time the pressing machine opens.

50. The accompanying drawings illustrate

one embodiment of the invention serving to show the principle and mode of operation of this invention. Certain changes may be made without departing from the scope of the invention.

Figure 1 illustrates a side view of a hosiery pressing machine constructed in accordance with my invention showing the press jaws open and illustrating one hosiery tray moved up into position between the jaws 55 while the other hosiery tray is in its lowermost position with one independent set of the hosiery forms pivoted or swung upwardly bringing the forms into position where the stockings are easily removed and replaced thereon.

Figure 2 shows a front view of the hosiery press with part of the hosiery forms broken away from the lower frame of the conveyer tray.

Figure 3 shows a separate view of the improved double unit hosiery tray provided with a double or twin set of hosiery forms each unit of which is pivotal independent of the other. Furthermore, this view illustrates printing tape in taut position stretched across the toes of the hosiery or forms of each independent unit in position ready to transfer the manufacturer's data such as size, trade mark etc., onto the work.

Figure 4 illustrates a cross-sectional view taken on the line 4—4 of Figure 3, but showing one work form unit pivoted outwardly from the other.

Figure 5 illustrates cross-sectional view 85 taken on the line 5—5 of Figure 5.

Referring further to the drawings for a detailed description of the invention, there is shown a tall vertical press frame 9 comprising in this instance two upright spaced frame standards 9 joined by connecting webs 10 and terminating at the upper end in hub bearings 11 which rotatably support a shaft 12 which carries lever arms 15 fixed thereto. The frame 9 is made with a bolting flange 13 on which is anchored a fixed pressing member such as a jaw or buck 14. The two lever arms 15 are shown reaching downwardly and are bolted to a movable pressing jaw or head 16. By rotating the shaft 12,

the pressing head 16 swings open and closed relatively to the buck 14 and presses the work therebetween.

- Means for oscillating the shaft 12 to operate the press includes a press lever 17 which has its upper end anchored to the shaft 12 and its lower end is adapted to be swung relatively to the frame to open and close the pressing jaws. The press lever 17 may be actuated by any suitable press operating means. In the present instance motor mechanism is employed for operating the press so that the lower end of the press lever is slotted as at 18 and by swinging the lower end of the press lever 17 it follows that the press jaw 16 is opened and closed on the work. To this end a crank arm 21 carries a roller 22 which travels in the press lever slot 18 to swing the press lever 17. The crank arm 21 is fixed on a drive shaft 23 and this shaft is driven by a worm wheel 24. A power driven worm pinion 25 engages the worm wheel 24; and a motor 26 drives the worm pinion 25. It is now observed how the electric motor 26, mounted on the frame 9 to the rear of the press, is adapted to open and close the pressing machine. It is apparent that mechanism other than that described may be used to oscillate the press lever. A control mechanism is employed to control the operation of the motor 26 and movement of the crank arm 21 in order that the press be stopped in open or closed position. For this purpose, the control of the motor may be accomplished by a foot pedal 27 pivoted on the frame and adapted to reciprocate a control rod 28. The upper end of the rod 28 is connected with a clutch lever 29 which is actuated to engage and disengage a clutch within an ordinary transmission housing 30 from which the drive shaft 23 projects and from which it receives its rotative power to operate the crank 21.
- In order that the work be conveniently and rapidly delivered and removed from the press jaws, an improved two-tray conveyer is used, each tray of which is equipped with twin garment forms. Two tray frames 31 and 32 are connected by cables 36 and 37, the pair of upper cables 36 running around supporting rollers 38 and being guided by spacing rollers 39 and the pair of lower cables 37 running around rollers 40 and being guided by spacing rollers 41. The supporting rollers 38 carry the weight of the conveyer trays and the work thereon, while the lower rollers hold the cables and trays at the desired angle, nearly upright, so as to run the trays in and out of the jaws parallel thereto. The guide rollers 39 and 41 act to confine the two trays 31 and 32 in close relation so as to enable both trays to be conveyed in and out of the jaws without providing excessively wide opening movement of the jaws. Tension springs 42 may be included in the cables to maintain

them taut and at the same time permit the head 16 to move the trays, particularly the outer or front tray 31, against the buck 14. The conveyer trays balance one with the other and readily run up and down by slight manual effort of the operator who grasps the lower tray and moves it upwardly which simultaneously pulls the upper tray down out of the press jaws to a position within reach of an operator.

While I have shown and described the improved double tray conveyer as used in connection with my upright pressing machine, it is apparent that it may be used with other types of pressing machines. Furthermore, the particular tray about to be described may in some instances be used independently of the conveyer apparatus because in certain cases this hosiery pressing and printing tray may be used singly on ordinary present day garment presses and the double or twin hosiery units in that event fulfills all requirements.

Since the construction and operation of both garment or hosiery trays 31 and 32 are alike, a description of one will suffice. A tray frame 31 carries a shaft 44 which has each end journaled in a reinforcement block 45 set in each corner of the frame 31. The shaft 44 is provided with means for holding it in fixed position and one satisfactory way to accomplish this result resides in the use of a notch 46 made in that end of the shaft which projects from the frame 31. A spring pressed locking dog 47 has one end of its spring 48 anchored to the frame 31 which causes the spring pressed dog 47 to yieldingly press in and out of the notch 46 to hold the shaft 44 in fixed position. It is the usual practice to make two notches 46 at an angle to each other in the shaft end 44 to lock it in either one or another position so that the shaft will remain where placed.

A tube 50 is rotatably carried on the shaft 44 with one end of the tube resting against the inner side of the frame 31 and the other end thereof projecting through the frame and being notched as at 51. A spring pressed dog 52 yieldingly presses into the tube notched at 51 to hold the rotatable tube in one or another position. This arrangement permits the shaft 44 and tube 50 to be concentrically rotatably mounted so as to allow one to operate independently of the other and each is locked in its respective position by the dogs 47 and 52.

Slots 54 are formed in the tube 50 at regular intervals and a garment form, such as a hosiery board or form 55 as shown, has one end thereof anchored in the shaft 44 and movably projecting through said slot 54. A plurality of hosiery forms 55 disposed in a common plane are anchored to the shaft 44 and swing therewith, thus constituting one of the units of the twin set hereinbefore men-

tioned. The forms 55 swing free and clear of the tube 50 and do not disturb its position.

Another set of hosiery forms 57 are arranged between the forms 55 and have their ends anchored to the tube 50 and are adapted to swing as the tube 50 rotates relatively to the shaft 44. This set of hosiery forms 57 constitute the other twin unit hereinbefore mentioned and operates independently of and does not disturb the position of the first mentioned unit 55. In other words, each hosiery form unit 55 and 57 moves independently of the other and the forms of each stand normally in the same plane.

It is to be observed that the last described hosiery forms 57 have long shanks 58 which place the toes of the forms 57 somewhat above the toes of the forms 55. In this way the toes of each of the twin forms are staggered or placed out of alignment with each other so that printing or transfer tape 59 may be disposed across the toes of all the higher forms 57, while another piece of printing or transfer tape 60 may be placed across the lower hosiery forms 55. The two printing strips 59 and 60 operate independently of each other and are adapted to transfer or print size data, the manufacturer's trade mark, or other indicia 61 directly onto the toes of each set of hose being pressed and printed. It is desirable to provide suitable anchorage means to hold the ends of the printing tapes 59 and 60, and to this end a spring clip 62 is placed on the frame at each end of the printing tape to hold it in taut condition across the hosiery toes.

The operator grasps a hosiery form 55 and pulls it out as in Figure 1 to swing all forms 55 constituting one unit out from the plane of the frame 31 so that hose can be easily removed therefrom and placed thereon. The operator in the same way actuates the other hosiery form unit 57. It is observed that the hosiery forms 55 are separated a considerable distance from each other when swung outwardly from the frame 31 or 32. However, when the forms are swung inwardly in common alignment, it follows that the forms 55 and 57 are disposed very closely together so as to economically utilize all space and to enable a large number of hose, say one dozen at a time, to be treated in one tray. By swinging one unit at a time outwardly, the operator has sufficient room in which to work because the hosiery forms 55 composing the unit are not in themselves crowded, neither are the hosiery forms 57 crowded, but when the twin units both of them are swung inwardly and made ready for pressing, it follows that the forms 55 and 57 are crowded up in close relation to economize space and increase production.

A work trough 65 may be placed directly beneath the conveyer apparatus, if desired,

for it is necessary that the operator be kept supplied with a quantity of damp hose which are to be pressed and it is the usual practice for the garments or hosiery to be brought in quantity from the dying vats and piled in the trough 65 whereupon the operator is supplied with sufficient work to fill first one hosiery unit 55 and the other 57.

In the general operation of a machine, the operator presses the control pedal 27 to stop the motor 26 or to actuate the clutching mechanism so as to open the press to position shown in Figure 1. The conveyer is then operated to bring one tray, as the tray 31, to lowermost position which simultaneously carries the loaded tray 32 upwardly into the jaws. The operator next presses the pedal 27 to close the head 16 upon the work. While one tray load of work is undergoing the pressing operation, the operator attends to the removal and placing of work upon the other lowermost tray which just came out of the jaws whereupon the pedal 27 is again actuated and the above mentioned procedure is repeated.

Special utility resides in the twin hosiery units 55 and 57. The twin set of forms are used to expedite the tape printing operation and to hasten production. Printing of hosiery cannot always be satisfactorily done until they are dried. It is therefore inadvisable to put wet hosiery on the forms and at the same time stretch the transfer tape thereacross for the reason that transfer tape will not satisfactorily imprint the data 61 on the hose when damp and during the drying operation.

It becomes desirable, therefore, to first dry the hose and thereafter print them. My invention, embodies means for first drying the hose by one closing operation, followed by opening the press; whereupon the operator stretches the printing tape in position; and immediately again closes the press to perform the printing operation. In other words, the hose on one of the form units, as the unit 57, is first dried by closing the press; the press next opens to give access to the dried work; the operator draws the printing tape across the dried hosiery toes; and the press then again closes the second time which satisfactorily effects the printing operation. In this way the press jaws must close twice on each hose to dry and print them. The jaws close first to dry the hose, and close the second time to print the hose.

Before the advent of my garment press improvements herein described, it was necessary for the pressing machine jaws to open and close twice before obtaining one set of completely dried and pressed hosiery. There followed loss of time because the work was removed from the press every pressing operation, but by employing this improved machine, it is possible to remove completely pressed and printed hosiery each and every

time the jaws open. This improved mode of operation is carried out by first filling one form unit, as 55, with wet hose and starting the pressing operation without having any hose mounted on the other unit. The press jaws are now first closed upon the one first filled unit 55, the jaws are then opened to expose the dry hose; the printing tape 60 is spread across the dried hose on this unit 55 and at the same time the operator now puts wet hose on the empty forms 57; runs the loaded tray up into the jaws; and initiates the pressing operation. Upon the second opening of the press jaws, it follows that one set of hose comes off of the unit 55 completely dried and printed and the wet hosiery which had been mounted on the forms 57 are dried only which means that the operator now stretches the other printing tape 59 across the toes on the forms 57, and this operation continues periodically with the result that one batch of hosiery is removed from the press completely dried and printed each time the jaws open.

25 The spring clips 62 enable the operator to quickly remove the old and used tape 59 and 60 and replace it with new tape. The operator of course uses one tape on every other form unit 55 or 57 each time the jaws open so that one new tape is used each time the press opens.

Figure 1 shows one of the hosiery units, as 55, swung outwardly from the frame 52 in a position convenient to the operator so that he may remove the hosiery therefrom and replace new goods thereon to be treated and it is understood how each unit 55 and 57 swing out freely from the tray frame while the work is being changed.

40 By using this improved hosiery press, it follows that economy in floor space is obtained, working conditions are more pleasant because the heat is not so intense, and production is greatly increased because the operator is actually engaged during each pressing period.

What I claim is:

1. A garment finishing tray comprising a frame, a plurality of sets of garment holding forms carried by the frame in one plane, each set being independently pivoted in relation with the other set and to swing laterally with respect to the frame, and each set of forms including a number of garment forms carried in fixed relation to each other to hold garments in shape during a finishing operation.

2. A garment finishing tray comprising a frame, a twin set of garment holding forms carried in one plane thereby, each set being in independent pivotal relation with the other set, each set including a plurality of forms, and means for holding each set in fixed relation in a position independently of the other.

3. A garment finishing tray comprising a

frame, a twin set of garment holding forms carried in alignment thereby, each set being in independent pivotal relation with the other set, each set including a plurality of forms, means for holding each set in fixed relation in a position independently of the other, and transfer tape holding means for supporting printing tape on the forms of each set.

4. A garment pressing tray comprising a frame, a shaft pivotally carried therein, a set of garment forms fixed to the shaft and movable in and out of the frame, another set of garment forms, and means for pivotally supporting the last set of forms adjacent the first set of forms.

5. A garment pressing tray comprising a frame, a shaft pivotally carried therein, a set of garment forms fixed to the shaft and movable in and out of the frame, a tube rotatably carried on the shaft, and a set of garment forms mounted on the tube.

6. A garment pressing tray comprising a frame, a shaft pivotally carried therein, a set of garment forms fixed to the shaft and movably in and out of the frame, a tube rotatably carried on the shaft, a set of garment forms mounted on the tube, the forms being alternately secured to the shaft and tube thus providing two independently operating units such that the forms of both units are closely spaced when standing in a common plane and distantly spaced when one unit is moved out from the other.

7. A garment pressing tray comprising a plurality of garment forms closely spaced in a single plane and movable in the tray, means for rigidly connecting together every other form, and a second means for rigidly connecting together the remaining forms thereby providing two groups of forms independently operable.

8. A garment pressing tray comprising, a frame, a shaft pivotally mounted therein, garment forms mounted on the shaft, a tube on the shaft and slotted at each form to permit the shaft and forms to pivot relatively to the tube, and garment forms mounted on the tube.

9. A garment pressing tray comprising, a frame, a shaft rotatably mounted therein, garment forms mounted on the shaft, a tube on the shaft and slotted at each form to permit the shaft and forms to pivot relatively to the tube, garment forms mounted on the tube, means to hold the shaft and its forms in a predetermined position, and means to hold the tube and its forms at any desired position.

10. A garment pressing tray comprising, a frame, a shaft rotatably mounted therein, garment forms mounted on the shaft, a tube on the shaft and slotted at each form to permit the shaft and forms to pivot relatively to the tube, garment forms mounted on the tube, and printing tape holding means car-

ried by the frame and adapted to hold the tape on one or both of the aforesaid forms.

11. A garment pressing tray comprising, a frame, a shaft rotatably mounted therein, garment forms mounted on the shaft, a tube on the shaft and slotted at each form to permit the shaft and forms to turn relatively in the tube, garment forms mounted on the tube, means to hold the shaft and forms at any desired position, means to hold the tube and forms at any desired position, and printing tape holding means carried by the frame and adapted to hold the tape on one or both of the aforesaid forms.

15. 12. A hosiery and the like pressing tray, a plurality of hosiery forms arranged in units, the forms of one unit being longer than the other and thereby being arranged in staggered relation thus producing two rows of forms, the hosiery toes of one row being in alignment and the hosiery toes of the other row being in alignment, and supporting means carrying the alternate hosiery forms of each row in independently movable relation whereby the operator progressively loads one row of forms with work and removes completed work from the other row of forms.

13. A press comprising in combination, a frame standing vertically, cooperating press jaws with uprightly disposed pressing surfaces mounted on the upper end of the frame high above the operator, a press lever adapted to swing the jaws open and closed, operating means for working the press lever, and a double tray carrier for conveying work up and down into and out of the jaws, and a twin set of garment forms mounted in each tray.

14. A press comprising in combination, a tall vertical frame, cooperating press jaws mounted on top the frame high above the position of an operator, said jaws having their pressing faces disposed at an angle to the vertical, means for opening and closing the press, a work conveyer mounted on the frame parallel to the plane of the press jaws in upright position at an angle to the vertical, and pivoted work forms carried by the conveyer adapted to pivot into the conveyer to move up into the jaws and pivot out after moving down from the jaws.

15. A press comprising in combination, a tall press frame, press jaws mounted on top of the frame, said jaws having their meeting faces in a substantially upright position, means for opening and closing the press, a plurality of tray frames, support means holding the frames parallel to the faces of the press jaws and to carry the frames to and from the jaws, and a plurality of work forms mounted in each frame and pivoted in relation thereto adapting the forms to swing in and out of the frame.

16. A hosiery press comprising in combination, a tall press frame, press jaws mounted

on top of the frame, said jaws having their meeting faces in a substantially upright position, means for opening and closing the press, a plurality of tray frames, conveyer support means holding the frames parallel to the faces of the press jaws and to carry the frames to and from the jaws, twin work form units carried in each frame thereby adapting hosiery to be progressively finished on first one unit and then the other, and means mounting each unit so it may be swung outwardly in relation to the other to a loading and unloading position.

17. A press comprising in combination, a tall press frame, press jaws mounted on top of the frame, said jaws having their meeting faces in a substantially upright position, means for opening and closing the press, a plurality of tray frames, conveyer support means holding the frames parallel to the faces of the press jaws and to carry the frames up to and down from the jaws, a plurality of work forms mounted in each frame and divided into units each of which is pivoted in relation to the other adapting the forms to swing in and out of the frame, and a printing means independently cooperating with each unit thereby enabling a quantity of work to be progressively dried and printed each jaw closing and pressing operation.

18. A press comprising in combination, pressing jaws, operating means for opening and closing the press, a pressing tray adapted to be placed between the jaws, means for moving the tray in and out of the jaws, a twin set of work forms carried in the tray, means for mounting said forms in the tray in two rows each row providing a set of forms, the work adapted to be dried and pressed by the jaws on one set of forms, printing means associated with the press to print the dried and pressed work on one set of forms, and printing means to print the work on the other set of forms.

In testimony whereof I affix my signature.
JAMES CAMROD LEDBETTER.
